UNITED STATES PATENT OFFICE.

HOWARD E. DOAN, OF JOLIET, ILLINOIS.

DOOR OPENING AND CLOSING MECHANISM.

1,347,844.

Specification of Letters Patent.

Patented July 27, 1920.

Application filed March 24, 1919. Serial No. 284,554.

To all whom it may concern:

Be it known that I, HOWARD E. DOAN, a citizen of the United States, and a resident of Joliet, in the county of Will and State 5 of Illinois, have invented certain new and useful Improvements in Door Opening and Closing Mechanism, of which the following is a specification.

My invention has reference to means for 10 controlling the movement of doors, gates and the like. More particularly stated, my invention relates to apparatus for opening and closing sliding or swinging doors, such as are employed on garages, barns, and similar 15 structures, and which will retain the doors in their closed positions.

The principle by which I propose to carry 20 out my invention comprises the provision of a depressible platform or table that is operated by the weight of the vehicle driven onto it, and which is connected to a tiltable track and guide, whereby a weight thereon is permitted to gravitate and move the door.

One of the divers objects of my invention 25 is the provision of a structure of this character that shall be entirely automatic in its operation to both open and close the door or doors so that the driver of the vehicle has not need to alight therefrom to unlock or 30 operate the door manually. Another object is to provide a structure that will automatically lock or hold the door securely in its closed position. It is frequently the case 35 in automatic door operating structures that they may be actuated by persons other than the proper ones, such as by children who might be playing around the building, and it is therefore a further object to provide an apparatus of this character that can only 40 be actuated by a considerable weight, say in excess of 500 pounds placed upon the depressible platform. Further objects are 45 simplicity and novelty of construction, ease of installation and operation, economy of space, and nominal cost of manufacture.

I prefer to accomplish the divers objects 50 of my invention in substantially the manner hereinafter fully described, and as more particularly pointed out in the claims, reference being now had to the accompanying drawings that form a part of this specification, and which are merely diagrammatic for the purpose of illustration.

In the drawings,—

Figure 1 is a vertical elevation of a portion 55 of a garage, showing my invention installed therein.

Fig. 2 is a plan of the entrance portion of the garage.

Fig. 3 is a central vertical section of the 60 depressible platform enlarged.

It will be understood that the principles of my invention are applicable to any type of door, gate or other similar closure for buildings, and I have, for the purpose of 65 convenience, illustrated my invention as applied to a single door of the sliding type for a garage. In the drawings, similar reference characters have been employed to designate the same parts throughout the 70 views.

By referring to Fig. 1, it will be observed 75 the wall of the garage 5 is provided with the usual doorway or opening 6, for the passage of vehicles, which opening is closed by a door 7, provided at its upper edge with suitable door hangers 8, the wheels whereof travel upon a horizontal track 9, extending along the top of the opening 6 and to one side thereof a distance substantially equal to the width of the door. Adjacent one end of the track is a tiltable arm 10, that is preferably fulcrumed near one end upon a pivotal bracket 11 secured to the wall of the building and has a deep channel or groove 12, in its upper surface to provide a guideway for a weight 13, of substantially globular or spherical shape. Oppositely projecting horizontal studs 14 are provided on the weights 13, and a bail 15 connects these studs and extends halfway around the weight in the manner shown, so as to afford means for connecting the same to the door through the medium of the flexible cable 16. The arm 10 is normally horizontal so that the weight will be positioned adjacent but slightly to one side of the fulcrum or pivotal bracket 11, in order that when the arm is tilted by lowering the longer end, the weight will roll down the guideway and pull the door open, a grooved roller or shive 17 being provided at the shorter end of the arm to permit the cable to slide freely over the same.

The arm is retained in its normal horizontal position by the following instrumentalities: 100

The arm is retained in its normal horizontal position by the following instrumentalities: 105

ties, to-wit:—A cable 18, or other suitable means, is connected at one end to the shorter end of the arm 10, while the opposite end of the element 18 is adjustably connected to the 5 outer portion of a lever 19, that is fulcrumed at its opposite end on a pivot bracket 20 secured to the wall or other convenient portion of the building. Another cable 21 or other suitable element connects this lever 19 to the 10 movable portion of the depressible platform 22, to which it extends over the pulleys 23.

Below the doorway, both inside and outside the building, I construct suitable pits 24, that may be of masonry or otherwise, as 15 desired, that are connected by passageways extending between their central portions. Embedded or otherwise mounted in the bottom of each pit, are base plates 25, from each of which arises a substantially tubular extension 26, of considerable diameter and the top or upper edges whereof terminate below the undersides of the platform, while their walls are provided with vertical slots 27, in 20 which horizontally disposed rocking arms 28 25 are fulcrumed intermediate their ends.

A tubular extension 29 depends from the underside of each platform 22, so that their lower portions telescope with the lower tubular elements 26, and are each provided with 30 a crosspiece 30, that coöperates with the inner end portion of the rock-arm 28. The outer ends of the rocker arms 28 extend toward each other in the channel which connects the pits, said arms terminating adjacent each other so that the elongated bail on 35 weight 31 may be suspended from the ends of both arms, as shown in Fig. 3 of the drawings. This weight 31 is sufficient to more than counterbalance the weight of the 40 platforms 22 and their tubular extensions 29,—in fact it is designed to keep the platforms normally up until an additional body weighing more than 500 pounds, such as the forward end of an automobile, is driven or 45 placed upon either platform, whereupon it will permit the platform to depress.

As before stated, the weight 31 keeps the platforms up, and in so doing retains the cables 18 and 21 normally taut, and of course 50 when either platform is depressed, the tension is removed from the cables, permitting the arm 10 to fall and the weight 13 thereon to gravitate down the groove or channel 12, pulling the door open. When the wheels of 55 the vehicle have moved off of the platforms, the large weight 31 will again elevate the platforms, causing the tightening of cables 18 and 21, which, in turn, elevate the arm 10 again to horizontal position. The door will 60 now be closed by the falling of an auxiliary weight 32 connected to the opposite end of the door by a cable 33, that passes over a pulley 34, it being understood that the door opening weight 13 is now movable in a horizontal plane and requires very little traction 65

to move it along its track, so that the weight 32 need not be large in proportion to the weight 13, although the latter is sufficient to elevate weight 32 when the door is being opened.

It will be obvious, after the heretofore described structure is understood, that divers changes are possible without materially departing from the principles involved, and I desire it understood that refinements and 75 modifications of my invention are contemplated as included within the scope of my appended claims.

What I claim is:—

1. In mechanism of the kind described a 80 horizontal stationary track, a door supported therefrom and movable thereon, a tiltable arm adjacent said door, a weight on said arm and movable toward and away from the fulcrum thereof, means connecting said weight 85 and door, a yielding member positioned adjacent the doorway adapted to hold said arm in neutral position in which the weight carried thereon will not gravitate, and means connecting said member to said arm whereby 90 the yielding of said member permits said arm to tilt and gravitate the weight carried by the latter and thereby move the door.

2. In mechanism of the kind described a 95 movable door, a tiltable arm adjacent thereto, a weight on said arm and movable toward and away from the fulcrum thereof, means connecting said weight and door, a depressible platform in front of the door, a 100 depressible platform on the opposite side of the door, means connecting said platforms to said arm, and means coöordinated with said platforms whereby the depression of either of said platforms permits said arm to tilt and 105 gravitate the weight carried thereby to move the door.

3. In mechanism of the kind described a 110 movable door, a tiltable arm fulcrumed adjacent one end to provide long and short sections upon opposite sides of the fulcrum, a 115 weight movable on the long section of said arm toward and away from the fulcrum, means connecting said weight and said door, a yieldable member adjacent the doorway, and means connecting said member to the 120 short section of said arm whereby said member normally holds said arm in neutral position in which the weight will not gravitate and the yielding of said member permits said arm to tilt and gravitate the weight carried by the latter to move the door.

4. In mechanism of the kind described a 125 movable door, a tiltable arm fulcrumed adjacent one end, a weight movable upon the larger portion of said arm and normally positioned adjacent the fulcrum, means connecting the weight and door, a yieldable member adjacent the doorway, and a cable connecting said arm to said member and kept taut by the normal position of said 130

member to hold said arm in horizontal position, whereby the depression of said member slackens said cable to permit said arm to tilt and gravitate said weight thereby moving 5 said door.

5. In mechanism of the kind described a 10 slideable door, a weight connected to said door to move the same in one direction, a tilttable supporting track for said weight, a 15 compressible platform, a cable extended taut from said platform to said track and normally holding the same in a horizontal plane to retain the weight inert whereby the depression of said platform by the weight of 20 a vehicle slackens said cable and permits the track to tilt to gravitate the weight and open the door and the return of said platform to normal position tightens said cable and elevates said track to a horizontal position.

25 6. In mechanism of the kind described a slideable door, a weight connected to said door to move the same in one direction, a tilttable supporting track for said weight, a 30 compressible platform, a cable extended taut from said platform to said track and normally holding the same in a horizontal plane to retain the weight inert whereby the depression of said platform by the weight of 35 a vehicle slackens said cable and permits the track to tilt to gravitate the weight and open the door and the return of said platform to normal position tightens said cable and elevates said track to a horizontal position, and an auxiliary weight connected to the door and elevated by the gravitation of

the first-mentioned weight whereby when said track is returned to horizontal position said auxiliary weight will move the door in the opposite direction and slide the first- 40 mentioned weight toward the fulcrum of the track.

7. A mechanism for automatically opening and closing doors comprising a movable platform, means for yieldingly maintaining said platform in an elevated position, a door, a weight arranged so that the gravity thereof tends to close said door, a second and preponderating weight connected to said door, a pivoted track for said prepon- 45 derating weight, and means actuated by the movement of said platform for inclining and restoring said track so as to cause said preponderating weight to alternately over- 50 come and permit the action of said first- 55 mentioned weight.

8. In combination with a gravity controlled door and devices for actuating said door, of means for retaining said devices normally inactive consisting of a suitable 60 pit positioned adjacent the doorway closed by said door, telescopic tubular members mounted in said pit, a platform carried by the upper tubular member, a lever extended through the lower tubular member and hav- 65 ing a weight upon its outer end and a cross rod carried by the upper tubular member and engaging the inner end of said lever.

Signed at Chicago, county of Cook and State of Illinois, this 19th day of March, 70 1919.

HOWARD E. DOAN.
